ATTORNEY.

UNITED STATES PATENT OFFICE.

THOMAS LLEWELYN, JR., OF PITTSBURGH, PENNSYLVANIA.

PROCESS OF ROLLING ROUND METAL BARS TO ELIMINATE LAPS, SEAMS, AND SCALE.

1,381,572.

Specification of Letters Patent. Patented June 14, 1921.

Application filed February 11, 1919. Serial No. 276,265.

To all whom it may concern:

Be it known that I, THOMAS LLEWELYN, Jr., a citizen of the United States, residing at Pittsburgh, in the county of Allegheny and State of Pennsylvania, have invented a new and useful Process of Rolling Round Metal Bars to Eliminate Laps, Seams, and Scale, of which the following is a specification.

10 This invention relates to process of rolling metal and more particularly to a process of producing round bars, the object being to produce rolled round metal bars without the usual "side seam" or bead which generally occurs in rolling round bars by the now known process.

Another object is to produce rolled round metal bars without the usual "scale" or flaky surface which occurs when rolling round metal bars, especially iron and steel.

With these objects in view the invention consists in the novel construction and arrangement of parts, hereinafter described, illustrated in the accompanying drawings, 25 and particularly pointed out in the appended claims, it being understood that various changes in the form, proportions, size and minor details of construction may be made within the scope of the appended claims, 30 without departing from the spirit or sacrificing any of the advantages of the invention.

In the drawings:

The twelve figures represent the twelve pairs of rolls, which compose, successively used from 1 to 12, the twelve operations in the process of rolling from a billet of the dimensions shown by the dotted lines in Fig. 1 a round iron or steel bar as indicated by Fig. 12.

To those skilled in the art it is well known that in producing round metal bars, from ten to twenty passes are usually made through the mill before the bar is delivered. The type of mill employed for this process is known as the "Merchant" or continuous mill, the billet of heated metal being fed into the first pass and guided successively through the other passes until it emerges in the shape desired, the object being to reduce the billet slowly enough to prevent spreading the "fiber" of the metal and rapidly enough to deliver the bar while the metal is still hot enough to be workable. On all mills now employed, the groove in the successive pairs of rolls generally alternate from square or approximately square to oval. The square

grooved rolls ordinarily are arranged with the corners of the square on the vertical and horizontal, that is the sides of the square would be at 45° to the horizontal side of the 60 rolls and the oval rolls with the longer dimensions of the oval on the approximate center between the pair of rolls. This has been thought to be the best arrangement of rolls to reduce a billet to a round stock, but 65 it very frequently happens that employing mills with this succession of rolls, produce "flaky" stock, that is the finished round bar has a "scaly" surface. This scale is usually caused by a too rapid reduction of the billet, 70 which causes the outer portion of the metal to become "loose", that is a sort of slight crystallization of the outer surface of the metal takes place. Scale also not infrequently occurs if too many passes are employed in the mill, thus allowing the metal to cool below the desired working point.

To overcome the objections in "Merchant" mills now known and employed I have designed after a careful study and experiment 80 the twelve pairs of rolls successively used as herein shown, and it is more especially the last six passes here illustrated, that are designed to properly work the metal to produce a bar without scale.

It will be noted that the first four passes illustrated in Figs. 1, 2, 3 and 4 will work the billet down to a substantially broad flat bar. Instead of the horizontal oval generally employed as the next pass I use a pair 90 of rolls having grooves which in cross section describe a common parabola, as shown in Fig. 5, which work the bar delivered from pass 4 inwardly from the sides to produce a bar with a blunt faced top and bottom and a slightly bulged center portion. The next pass illustrated in Fig. 6 works it out once more into a flattened bar slightly smaller than the bar delivered from pass 4. The bar emerging from pass 6 is then run 100 between perfectly flat rolls in the next two passes shown in Figs. 7 and 8, which reduce it to the dimensions illustrated by the dotted lines in Fig. 9. The bar is inserted through pass 9 as indicated by the said dotted lines. 105 It will be seen that the bar will not be permitted to spread greatly at the sides in running through pass 9, which is also of the double parabola shape, the pressure from the rolls of this pass being directed against 110 the ends of the bar and forcing the central portion against the inclined sides of the

grooves in the rolls. The peculiar action thus produced on the metal prevents the sides from splitting away as is the case when a diagonally squared bar is run through a 5 horizontal oval pass. The next steps 10 and 11 produce the same effect upon the bar as 8 and 9 respectively. Emerging from pass 11 the bar is now ready for the finishing 10 pass. It will be seen by referring to the dotted lines of Fig. 12 that the pressure from the rolls in this figure will be substantially similar to the pressure of the rolls on passes 9 and 11 upon the bars of the shape 15 illustrated in Fig. 9, that is a constant pressing in of the ends while the intermediate portion is brought in contact at the bottom edge of the grooves.

While I have described my process as used on but one type of mill it is obvious that any 20 guide, bar, Merchant and continuous mills may be employed.

I claim:

1. The method of rolling round bars consisting in rolling a billet into substantially 25 rectangular cross sectional shape, then rolling the product into substantially oval cross sectional shape, then rolling the product into substantially rectangular cross sectional shape, then rolling the product again into 30 oval cross sectional shape, then rolling the product flat, then rolling the product again

into oval cross sectional shape and finally rolling the product into circular cross sectional shape.

2. The method of forming round bars 35 from metal, consisting in rolling a billet into successive rectangular cross sectional shapes of different sizes, then rolling the product into oval cross sectional form, then rolling the product into rectangular cross sectional 40 form, then rolling the product flat, then rolling the product again into oval cross sectional shape, then rolling the product again flat and finally rolling the product 45 into circular cross sectional form.

3. The method of forming round bars consisting in rolling a billet into rectangular cross sectional shape, then rolling the product into oval cross sectional shape, then rolling the product into rectangular cross sectional shape, then rolling the product flat, then rolling the product into oval cross sectional shape of less area than the first oval 50 shape, then flattening the product, then rolling the product into oval cross sectional 55 shape of less area than the second oval shape and finally rolling the product into circular cross sectional shape.

In testimony that I claim the above, I have hereunto subscribed my name.

THOMAS LLEWELYN, JR.
